UNITED STATES PATENT OFFICE.

CARL GUSTAF HEDBOHM AND SVANTE WILLIAM SIXTUS LINDBY, OF VISBY, SWEDEN.

GATHERING-COVER FOR HOLDING PAPERS.

1,129,673.

Specification of Letters Patent. Patented Feb. 23, 1915.

Application filed August 14, 1912. Serial No. 714,958.

To all whom it may concern:

Be it known that we, CARL GUSTAF HEDBOHM and SVANTE WILLIAM SIXTUS LINDBY, both subjects of the King of Sweden, and 5 residing at Visby, in the Kingdom of Sweden, have invented new and useful Improvements in Gathering-Covers for Holding Papers, of which the following is a specification, reference being had to the 10 drawings accompanying and forming a part hereof.

Our invention relates to improvements in gathering covers for holding papers, letters and the like, of the type in which bows or 15 hooks fastened to the cover are inserted through holes punched through the paper. In such covers as heretofore constructed it is customary that the punching of the holes and the insertion of the hooks are two separate operations, requiring appreciable time 20 and labor.

The object of our invention is to accomplish such a cover in which the punching of the holes and the insertion of the hooks 25 shall be performed in one operation and in an automatic manner simply by placing the paper into the cover and by folding the cover together.

To gain this object our invention consists 30 in a combination with the cover of means for punching holes in the paper, and means for inserting holding hooks into said holes, all of said means being arranged to operate automatically upon folding the cover, by 35 which combination we save considerable time and labor. In constructing the cover we use in combination with mechanism for punching the holes another mechanism for lifting the paper so that the punched holes 40 will be located just opposite to the ends of the aforesaid hooks.

Our invention is illustrated in the accompanying drawings in which—

Figures 1, 2 and 3 show sectional end 45 views of the cover and its punching mechanism, Fig. 4 shows a side view of the punching and lifting mechanisms, Fig. 5 shows the cover from above together with two punching mechanisms and a locking arrangement, Fig. 6 shows the back side of 50 the cover with the outer covering removed.

Referring to the drawings in detail 1 represents the back of the cover, made in two parts hinged together at 2. Four hooks 3 are fastened to the back of the cover. Each 55 punching mechanism comprises two supports 4 formed with a slot in which the pin of the hinge 2 can slide. Between the supports are placed two rotatable steel rollers 5, and also two plates 6 fastened to the hinge 60 pin. Two punches 7 are mounted upon one of said plates, the other one being formed with corresponding dies. Upon the outer side of each plate are placed two wedge shaped steel bars 9, against which the rollers will press and thereby cause the movement of the plates. To one of the plates are fastened three springs, of which the two, 65 designated by 8, will serve to withdraw the paper from the punches 7, and the third one 70 27, will move the plates apart.

11, 11 represent studs, and 12 steel plates fastened to the back and serving to move the supports and the rollers up and down.

Upon the left side of the punching mech- 75 anism in Figs. 1-3, is fastened a plate drum 10 for carrying away the paper chips, to the back of the cover.

The lifting mechanism is illustrated in Fig. 4. It comprises a support 13 fastened 80 to the hinges, and equipped at one end with a riser 15, upon which a cylinder 14 is ar- ranged to slide up and down. The cylinder and riser are provided with longitudinal slots in which the paper is inserted. On 85 each side of the cylinder is mounted a spring 21 serving to clamp the paper. The lifting of the cylinder with the paper is done by means of the two angular levers 16 and 18 and the stud 19 fastened to one half of the 90 back which stud will depress the lever arm 18 when the cover is folded. The cylinder is brought down again by means of the spring 17, acting on the angular lever 16.

The punching and lifting mechanisms are 95 prevented from dropping into an oblique position partly by the springs 26 fastened to the back, and partly by the hinge arrange- 100 ment 20 and 37 (Fig. 6). In said hinge arrangement a support is located extending upward between the two parts of the back of the cover and adapted to hold the angu-

lar lever 18 in proper position and to facilitate its coöperation with angular lever 16.

The locking arrangement is shown in Fig. 5. It consists of a spring 24 fastened to one half of the back and provided with a hole arranged to engage a hook or pawl 25 fastened to the other half. The cover is opened through the depression of the button 23 by which the rod 22 is turned and by means of an arm on its inner end lifts the spring 24, so that it becomes disengaged from the pawl 25.

The paper is inserted into the cover in the following manner: By depressing the button 23 the cover is opened as far as possible (Fig. 3), and the paper is placed in the punching arrangement between the left hand plate 6 and the springs 8, and also between the springs 21 in both of the lifting arrangements, the paper being brought down as far as the slots will allow. When the cover is being folded the plates 12 will move the supports 4 together with the rollers 5 upward in relation to the plates 6, so that the rollers will press against the wedge shaped bars 9 and thereby bring the plates 6 toward one another (Fig. 2). The punches 7 will then pierce the paper. Upon the continued motion upward of the supports 4, the rollers 5 will pass over the upper edges of the wedges 9, and the spring 27 will move the plates 6 apart, so that the springs 8 will withdraw the paper from the punches 7. Immediately thereupon the studs 19 (Fig. 4) will act on the levers 18 in the two lifting mechanisms so that they will lift the paper just so high that the punched holes come opposite to the free ends of the hooks 3 when they are about to meet. The paper will now slide on to the hooks. When the cover is entirely closed the supports 4 will have been brought down by the studs 11 to the position shown in Fig. 1, and are thus located together with the other parts of the punching and locking arrangements between the two wooden parts of the back.

From the above description it is clear that the operation of punching the holes in the paper and also the operation of lifting the paper to a suitable height, so that it may be caught by the hooks 3, are both performed entirely automatically by the closing or folding of the cover, whereby a considerable amount of labor and time may be saved.

55 We claim:

1. In a gathering cover for holding papers, the combination of means for punching holes in the paper, and means for inserting holding hooks into said holes, all of said means arranged to operate automatically upon the paper when folding the cover.

2. In a gathering cover, the combination of a punch and die for punching a hole in a paper, means for keeping the paper in

definite relation to the punch and die, means actuated by the folding of the cover for operating the punch and die, means actuated by the folding of the cover for operating the first-mentioned means to withdraw the paper from the punch, a hook, and means for inserting the hook into the hole.

3. In a gathering cover, the combination of a back formed in two pieces hinged together, a plate fastened to each piece, a support arranged to be actuated by the plates, rollers journaled in the support, a punch and die, means for holding a paper between the punch and die, and an operative connection between the rollers and the punch arranged to close the punch and die when folding the cover.

4. In a gathering cover, the combination of a back formed in two pieces, a hinge connecting the pieces, two plates (6) fastened to the hinge, one of said plates being formed with a die, a punch fastened to the other plate and arranged to correspond with the die, means for holding a paper between the punch and the die, and an operative connection between the plates and the hinge, arranged to actuate the punch and die so as to pierce the paper when folding the cover.

5. In a gathering cover, the combination of a back formed in two pieces, a hinge connecting the pieces, two plates fastened to the hinge, one of said plates provided with a die, a drum fastened to the same plate opposite to the die, a punch fastened to the other plate and arranged to match the die, means for holding a paper between the punch and die, and an operative connection between the plates and the hinge arranged to actuate the punch and die so as to punch the paper when folding the cover, the drum being arranged to receive the punchings.

6. In a gathering cover, the combination of a back formed in two pieces, a hinge connecting the pieces, two plates fastened to the hinge, one of said plates provided with a die, a punch fastened to the other plate and arranged to match the die, means for holding a paper between the punch and die, an operative connection between the plates and the hinge arranged to actuate the punch and die so as to punch the paper, and means for automatically operating the paper-holding means to withdraw the paper from the punch upon folding the cover.

7. In a gathering cover, the combination of a back formed in two pieces, a hinge connecting the pieces, two plates fastened to the hinge, one of said plates provided with a die, a drum fastened to the same plate opposite to the die, a punch fastened to the other plate and arranged to match the die, means for holding a paper between the punch and die, an operative connection between the plates and the hinge arranged to actuate the punch and die, and means for automatically operating the paper-holding means to withdraw the paper from the punch upon folding the cover.

plates and the hinge arranged to actuate the punch and die, means for operating the paper-holding means to withdraw the paper from the punch, a hook fastened to the back, 5 and automatically operating means for lifting the paper so that the punched holes will come opposite to the end of the hook, all

arranged to operate automatically, substantially as described.

CARL GUSTAF HEDBOHM.

SVANTE WILLIAM SIXTUS LINDBY.
